UNITED STATES PATENT OFFICE.

FRANCIS M. CASE, OF CLEVELAND, OHIO, ASSIGNOR OF ONE-HALF TO C. S. BRITTON
AND ONE-HALF TO JAMES E. DOYLE, BOTH OF CLEVELAND, OHIO.

SUCTION APPLIANCE.

1,278,852.

Specification of Letters Patent. Patented Sept. 17, 1918.

Application filed September 29, 1914. Serial No. 864,040.

To all whom it may concern:

Be it known that I, FRANCIS M. CASE, a citizen of the United States, residing at Cleveland, in the county of Cuyahoga and State of Ohio, have invented a new and useful Improvement in Suction Appliances, of which the following is a specification, the principle of the invention being herein explained and the best mode in which I have contemplated applying that principle, so as to distinguish it from other inventions.

My invention is particularly associated with the relative configuration of such parts of the motor and fan as surround the required bearing surfaces.

The specific object, besides providing a durable, simple and hence economical improvement, is to protect the lubricant upon the bearing surfaces, from the suction effect of the impeller. The means which I have devised for preventing the subjection of such bearing surfaces to the damaging tendency on the part of a sustained flow of air to dry, while simple is quite efficacious.

My inventive conception is associated with means which are hereinafter explained and variously combined in the claim. While the annexed drawing and particular description thereof, set forth in detail the preferred form embodying my invention, it should be understood that the means only exemplifies one of many diversified mechanical forms with which the principle of my invention may be properly applied.

Adverting to the drawing:

Figure I is part elevation, part section of a construction embodying my invention.

Fig. II is a similar view on a transverse line of vision.

The structure illustrated in the drawing will be seen to comprise an electric motor A having a laterally projecting bearing a' in which a motor shaft a² is movable and from which such shaft projects a given distance as seen in Fig. II. The motor A is mounted upon any suitable type of base B including, however, as a portion of its top a surface b' located underneath the projecting bearing a'.

The pair of complementary annular casing members C and D having concave sides opposed to and spaced from each other, are held in such position in a manner now described, and are adapted to inclose the revoluble impeller. The casing member C is provided below with a transversely extend-

ing flange c' adapted to rest upon the surface b' and be secured thereto in any approved manner. The flange c' is connected with the upper portion of the casing member C by means of a pair of stiffening webs c². The outer circumference of the casing member C is fashioned as an outwardly bent angular flange c³, while centrally such casing member is provided with an opening c⁴ somewhat larger than the bearing a'. The complementary casing member D involves a centrally flared portion d' in connection with an opening d² above, and its outer circumference is similarly fashioned as an outward-bent angular flange d³. The casing members C and D are secured to each other in the desired position by means of a pair of complementary securing rings E and E'. Below the rings E and E' are enlarged and constitute wholly tangential extensions e and e' as seen in both of the figures in the drawing. The casing members C and D are secured to the inner annular edge of the rings E and E' respectively by means of a plurality of rivets e². Similarly the outwardly disposed flange edges of the rings E and E' are affixed to each other by a plurality of circumferential and tangential rivets e³. As so arranged the opening c⁴ is disposed substantially opposite the opening d² and merely hindered of direct connection therebetween because of the interpositioning of the impeller to be described in the next paragraph.

An impeller F is carried at f' upon the projecting end a² of the shaft and includes in its structure a plurality of radially disposed vanes f². The shape of the vanes f² is such that the revolution thereof produces a strong suction effect or flow in the direction from the openings c⁴ and d² and toward the tangential exhaust outlet. Heretofore, so far as I am aware, the objectionable tendency of an atmospheric disturbance to dry a lubricated bearing has been allowed full play. It is for the purpose of precluding the possibility of such an occurrence that I have designed the impeller F so as to carry a collar f³ adapted to project through the opening c⁴. The collar f³ is spaced from the edges of the opening c⁴ and furthermore extends both beyond the outer side of such edge and the extremity of the bearing a' a sufficient distance to divert the induced flow of air from the latter. In accordance with my constructions the air current rushes in the

direction of least resistance through the opening c^4 outwardly adjacent the collar f^3 and thereafter is impelled by the vanes f^2 in the ordinary way. Practice has demonstrated conclusively that the bearing of an extremely high speed motor like the one here described is absolutely relieved of avoidable friction whereby its working life and efficiency are increased.

10 I claim:—

A suction appliance comprising, an electric motor frame having a bearing, a motor shaft rotatable therein and projecting therefrom, a casing provided with induction and discharge openings, the induction opening being intersected by said shaft, an impeller carried on the projecting end of said shaft

close to said bearing, said impeller being movable in said casing and between said openings, and a collar carried interiorly by said impeller and projecting out through the induction opening so as to be interposed between the edge of the latter and the end of said bearing, said collar extending beyond the end of such bearing in a direction reverse to that of the projecting portion of said shaft whereby to ward off from such bearing the counter air current passing through such induction opening.

Signed by me, this 12th day of Sept., 1914. :
FRANCIS M. CASE.
